(57) **CLAIM**

The ornamental design for a sponge with an emoji face, as shown and described.

DESCRIPTION

FIG. 1 is a front perspective view of a sponge with an emoji face, showing my new design;

FIG. 2 is a front elevational view thereof, the rear elevational view being a mirror image thereof; and,

FIG. 3 is a left-side elevational view thereof, the right-side elevational view, top plan view, and bottom plan view all being identical thereto.

1 Claim, 2 Drawing Sheets

FIG. 1

FIG. 2

FIG. 3
